UNITED STATES PATENT OFFICE.

HENRY W. SCHNEIDER, OF LITTLE OLEY, ASSIGNOR TO THE COLEBROOK-DALE IRON COMPANY, OF DOUGLAS TOWNSHIP, PENNSYLVANIA.

DESIGN FOR A SAD-IRON HANDLE.

SPECIFICATION forming part of Design No. 19,204, dated July 9, 1889.

Application filed April 15, 1889. Serial No. 307,342. Term of patent 14 years.

To all whom it may concern:

Be it known that I, HENRY W. SCHNEIDER, a citizen of the United States, residing at Little Oley, in the county of Berks and State of Pennsylvania, have invented and produced a new and original Design for Handles of Sad-Irons, of which the following is a specification.

Figure 1 is a side view of a sad-iron having my newly-designed handle. Fig. 2 is an end view of the iron and showing the hand-grasp of the handle in section.

The leading feature of my design consists in a sad-iron handle provided with rounded corners and inclined posts of substantially uniform diameter or thickness, as shown.

In the drawings accompanying this specification the same is shown as composed of the horizontal and straight hand-grasp part *a*, slightly-inclined posts *b*, and curved elbow

parts *c*, uniting the said hand-grasp and posts. The outlines or contours of the hand-grasp part *a* and the posts *b* are connected and continued by the curved elbows *c*, which in cross-section have the same size or dimension as said parts. The entire handle therefore presents to the view neither angles, notches, nor other irregularities to detract from its appearance of continuous uniform size in its several parts.

I claim—

The design for a sad-iron handle, as herein shown and described.

In testimony whereof I affix my signature in the presence of two witnesses.

HENRY W. SCHNEIDER.

Witnesses:

JOHN E. MORRIS,
JNO. T. MADDOX.
